UNITED STATES PATENT OFFICE.

JOSIAH CLAYBORNE TRAYLOR, OF EDNA, TEXAS.

DESIGN FOR A FLOWER-POT.

46,645.

Specification for Design.

Patented Nov. 10, 1914.

Application filed August 27, 1914. Serial No. 858,984. Term of patent 7 years.

To all whom it may concern:

Be it known that I, JOSIAH C. TRAYLOR, a citizen of the United States, residing at Edna, in the county of Jackson and State of Texas, have invented a new, original, and ornamental Design for Flower-Pots, of which the following is a specification, reference being had to the accompanying drawing, forming part thereof.

The figure is a perspective view of a flower pot, showing my new design.

I claim:

The ornamental design for a flower pot, as shown.

JOSIAH CLAYBORNE TRAYLOR.

Witnesses:

JOHN O. ROWLETT,
R. B. TRAYLOR.
